UNITED STATES PATENT OFFICE.

COURTLAND F. CARRIER, JR., OF ELMIRA, NEW YORK.

APPARATUS FOR DECOMPOSING ALKALI-METAL AMALGAMS.

No. 908,545.

Specification of Letters Patent.

Patented Jan. 5, 1909.

Application filed May 25, 1907, Serial No. 375,645. Renewed November 17, 1908. Serial No. 463,062.

To all whom it may concern:

Be it known that I, COURTLAND F. CARRIER, Jr., a citizen of the United States, residing at Elmira, in the county of Chemung 5 and State of New York, have invented certain new and useful Improvements in Apparatus for Decomposing Alkali-Metal Amalgams, of which the following is a specification.

10 The object of this invention is to provide an improved apparatus for decomposing alkali metal amalgams by the application of local electrolytic action.

It is well known that the reaction between 15 sodium amalgam and water is expedited by local action, and various devices utilizing this effect have been suggested. Thus it has been proposed to oxidize the amalgam in a metal container, but it has been found that 20 in such case the mercury is subject to contamination by the metal of the container. Carbon has been used in various ways to form a couple with the amalgam, as by forming the sides of the container of carbon plates, or 25 by floating pieces of carbon upon the amalgam. Various devices have also been employed to secure more efficient contact between the carbon and the amalgam, as by incorporating metallic filings with the carbon 30 or otherwise providing metal surfaces in contact therewith, or by providing the carbon with secondary or roughened surfaces. I have discovered that graphite offers particular advantages for this purpose. The amalgam wets the graphite surfaces and makes 35 effective electrical contact therewith; and owing to the high electrical conductivity of graphite as compared with carbon it forms a more efficient couple with the amalgam and 40 the oxidation of the alkali metal proceeds at a higher rate. In practice I preferably employ graphite in the form of plates or bars extending above the surface of the amalgam to a sufficient height to permit a substantial difference in the density of the caustic alkali 45 solution in contact with the bars, this height being preferably not less than two inches. I have found that unless the graphite is in contact with liquid strata differing substantially 50 in density the action is very slow, and the arrangement of the apparatus should be such as to facilitate the production and maintenance of such strata.

A preferred form of apparatus in accordance 55 with my invention is shown in the accompanying drawing, wherein:

Figure 1 is a vertical longitudinal section of the apparatus on line 1—1 of Fig. 2; and Fig. 2 is a transverse vertical section of the same.

The apparatus shown comprises a containing vessel 1, preferably of concrete but which may be of any suitable material, the bottom being smooth and preferably very slightly inclined toward the outlet for mercury. In 60 case it is desired to collect hydrogen the container is provided with a cover 2 having an outlet pipe 3 therein.

4, 5 represent respectively the inlet for amalgam and the outlet for mercury, these 70 pipes entering through the bottom of the cell and being arranged to constitute seals to prevent the escape of solution. The container is also provided with an inlet pipe 6 for water or an oxidizing electrolyte approximately at the normal solution level, and an outlet 7 for the caustic alkali solution constructed to maintain the liquid level while withdrawing the denser solution from a point adjacent the surface of the mercury 8. The 75 decomposing couple proper comprises a number of graphite plates or bars 9, preferably disposed substantially at right angles to the general direction of flow of amalgam between inlet and outlet; these plates are spaced by 80 heavy iron bars 10, and the whole is assembled by bolts 11. The bars 10 should be sufficiently heavy to insure the stability of the couple even in the presence of a considerable depth of mercury and when completely 85 immersed in a caustic solution of high concentration. The bottom of the bars are recessed, grooved or perforated as illustrated at 12, the recesses in adjacent bars being 90 preferably in staggered relation to direct the amalgam in a tortuous path and thoroughly 95 agitate it. This stirring or agitation of the amalgam is of great importance as the alkali metal is thereby carried to the surface for oxidation. The couple is preferably completely 100 immersed in the solution, the normal level of which is indicated in the figures by dotted lines.

The reaction occurs at the line of contact between the solution, the amalgam and the 105 graphite, and other factors constant, the amount of alkali metal oxidized is proportionate to the length of this line of contact; accordingly the recesses 12 should be of such dimensions and so spaced as to insure the 110 greatest practicable length of contact. The preferred dimensions and spacing of the re-

cesses will of course vary with the thickness of the graphite plates or bars. Employing plates one inch in thickness, twenty-five inches in length and three inches deep I have found it advantageous to provide recesses one-half inch wide at the level of the amalgam and spaced one and one-half inches apart, thereby increasing the line of contact in this particular case by about twenty per cent. It is preferable that the recesses should be not less than one-half inch wide at the amalgam level, and therefore the graphite plates or bars should preferably exceed one-half inch in thickness in order that the contact line may be increased.

15 I claim:

1. Apparatus for decomposing alkali metal amalgams comprising a vessel containing the amalgam, an electrolyte in contact with the amalgam, and a body of graphite in contact with said amalgam and electrolyte.

2. Apparatus for decomposing alkali metal amalgams comprising a vessel containing the amalgam, an electrolyte in contact with the amalgam, a body of graphite in contact with said amalgam and electrolyte, and a weight for maintaining such contact.

3. Apparatus for decomposing alkali metal amalgams comprising a vessel containing the amalgam, an electrolyte in contact with the amalgam, and a plurality of spaced plates of graphite in contact with said amalgam and electrolyte.

4. Apparatus for decomposing alkali metal amalgams comprising a vessel containing the amalgam, an electrolyte in contact with the amalgam, a plurality of spaced plates of

graphite in contact with said amalgam and electrolyte, metallic weighting and spacing bars for said plates, and bolts assembling 40 said bars and plates.

5. Apparatus for decomposing alkali metal amalgams comprising a vessel containing the amalgam, an electrolyte in contact with the amalgam, a plurality of spaced plates of 45 graphite in contact with said amalgam and electrolyte, recesses in the bottoms of said plates, and an inlet for amalgam and outlet for mercury on opposite sides of said plates.

6. Apparatus for decomposing alkali metal amalgams comprising a vessel containing the amalgam, an electrolyte in contact with the amalgam, a plurality of spaced plates of 50 graphite in contact with said amalgam and electrolyte, recesses in the bottoms of said 55 plates disposed in staggered relation in adjacent plates to afford a tortuous path for the flow of the amalgam, and an inlet for amalgam and outlet for mercury on opposite sides of said plates.

7. Apparatus for decomposing alkali metal amalgams comprising a vessel containing amalgam, an electrolyte in contact with the amalgam, an inlet for the electrolyte at the normal liquid level, a solution outlet in proximity to the surface of the amalgam, and a body of graphite in contact with said amalgam and electrolyte.

65 In testimony whereof, I affix my signature in presence of two witnesses.
